UNITED STATES PATENT OFFICE.

MATHIAS WEISSER, OF MILWAUKEE, WISCONSIN.

GAS-ENGINE.

1,099,955.

Specification of Letters Patent. Patented June 16, 1914.

Application filed May 6, 1912. Serial No. 695,371.

To all whom it may concern:

Be it known that I, MATHIAS WEISSER, a citizen of the United States, residing at Milwaukee, county of Milwaukee, and State 5 of Wisconsin, have invented new and useful Improvements in Gas-Engines, of which the following is a specification:

My invention relates to improvements in gas engines, and it pertains, among other 10 things.—First, to the construction and relative arrangement of the power cylinder, piston, valves and all the operative mechanism of the engine with the supporting inclosure of such parts, whereby such supporting inclosure is adapted to form a receptacle for 15 a fluid lubricant, which lubricant, when placed therein, is caused by the movement of the engine to be continuously splashed by the revoluble movement of the crank and 20 otherwise conveyed to all of the moving parts of the engine, whereby the friction is diminished and the wear of the engine is reduced to the minimum. Second, to the relative arrangement of the power piston to 25 the inlet and outlet gas controlling valves, whereby the movement of one of said valves is substantially counter-balanced by the movement of the other, and whereby the vibration of such valves is diminished, and, 30 third, to the device for controlling the relative strokes of the outlet and inlet gas controlling valves to correspond with the movement of the power piston.

My invention is further explained by reference to the accompanying drawings, in which—

Figure 1 represents a horizontal section drawn on line $x-x$ of Fig. 2. Fig. 2 represents a vertical section drawn on line $y-y$ of Fig. 1. Figs. 3 and 4 represent horizontal and vertical sections of a modified form of the engine shown in Figs. 1 and 2.

Like parts are identified by the same reference numerals throughout the several 45 views.

1 is a power cylinder into which the explosive gas is led, compressed and exploded.

2 is a power piston which is connected with the driving shaft 3 through the pin 4, 50 connecting rod 5, crank pin 6 and crank 7 in the ordinary manner. Gas is led to the valve chamber 8 through the inlet port 9, and it passes from thence into the cylinder 1 through the valve 10 and valve port 11.

The valve 10 comprises the annular sleeve 55 12 provided with radial ports 14 and central partition 13. The radial ports 14 connect with the stationary annular channel 11 which connects with the cylinder 1 through the port 11', and said valve is adapted, with 60 each reciprocating movement of the piston, to be brought into communication with the port 11', leading to the cylinder. Motion is communicated to said valve 10 from the main driving shaft 3 through the gear 15, 65 indicated by dotted lines, in Fig. 2, gear 16, gear supporting shaft 17, crank pin 17', crank 18, connecting rod 19, valve pin 20 and pin supporting lugs 21. Motion is also simultaneously communicated to the exhaust 70 valve 22 from said main driving shaft 3 through said gear 15, gear 23, gear supporting shaft 24, crank 25, crank pin 26, connecting rod 27, valve pin 28 and pin supporting lugs 29, and the relative size and 75 position of said gears and pistons to each other are such that the piston 2 is moved back, (reference being had to Figs. 1 and 2), in the act of drawing gas and air into the cylinder 1 as the inlet port 11', leading 80 to said cylinder, is opened, while the outlet port 30, leading from said cylinder, is closed by said valve 22, whereby a partial vacuum is formed in the cylinder as the piston is drawn back by the momentum of the fly 85 wheel, not shown, whereby gas and air are caused to enter said cylinder, as stated, preparatory to being compressed and exploded. The relative size and position of said gears, 90 pistons and valves to each other is such that both the inlet and outlet ports leading to and from said cylinder 1, are closed with the next forward movement of the piston, whereby the explosive mixture which has previously been drawn into said cylinder is 95 confined and compressed preparatory to being exploded. When the gas and air have been compressed and exploded and the piston again thrown back, as stated, the inlet valve will remain closed while the outlet valve will be opened, when the products of combustion will be forced out from said cylinder through the duct 30, annular channel 30', and thence inwardly through the radial ports 32', from thence out through the center of the valve 22 and outlet 31, when the movement thus described will be again and 100 continuously repeated. The outlet valve 22 105

comprises the vertical sleeve 32 provided with radial ports 32' and the transverse partition 33.

35 is a water jacket of ordinary construction.

It will be understood that the engine thus far described is provided with an igniting mechanism of ordinary construction, which is connected with the operative mechanism

10 of the engine in such a manner that a spark is produced and the gas is ignited at the proper moment as soon as the same is compressed by the forward movement of the piston, as previously described.

15 By the modified form of the engine shown in Figs. 3 and 4, two additional pairs of gears 36 and 37 are interposed between the gear 39 carried by the main driving shaft 3 and the gears 40, 40 carried by the valve 20 actuating shafts 17 and 24, whereby the relative movement of the reciprocating valves 10 and 22 to that of the piston 2 is reduced and whereby said valves in said modified form are adapted to make but one stroke to 25 every four strokes of the power piston, while by the preferred form shown in Figs. 1 and 2, the gas controlling valves make one stroke for every two strokes in the power piston. In all other material respects, the modified 30 form shown in Figs. 3 and 4 is substantially the same as that shown in Figs. 1 and 2, and the several coöperating parts are referred to by the same reference numerals. To provide for packing the inlet and outlet valves and 35 taking up wear, the respective valve chambers are made slightly larger than the valves, thus providing for the reception of the packing sleeves 40, and said packing sleeves are each provided with a pair of resilient pack- 40 ing rings 41, 41 which are retained in annular recesses provided therefor in said packing sleeves upon the respective upper and lower sides of said annular channels. Said resilient rings and said sleeve are respec-

tively retained in place by the annular 45 sleeves 42, which sleeves are in turn retained in place by the heads 43 of said valve cylinders. It will, of course, be understood that the resilient packing rings are adapted to form a tight joint between the inclosing 50 bearings of the cylindrical valves which they inclose.

Having thus described my invention, what I claim as new, and desire to secure by Letters Patent, is—

55 In a gas engine, the combination with a power cylinder, two valve chambers connected with the opposing sides of said cylinder, each valve chamber being provided with a packing sleeve, each packing sleeve being 60 provided with an annular recess upon its inside for the reception of a resilient packing ring, said ring bearing inwardly against the exterior surface of the valves, and an intermediate annular channel, one of said 65 intermediate channels being formed for the passage of an explosive mixture to said cylinder and the other for the escape of the burned products of combustion from said cylinder, a hollow cylindrical valve located 70 in each of said packing sleeves provided with a plurality of radial ports adapted to communicate between the central space in said valve and the intermediate annular inclosing channel, said valves being also each 75 provided with a transverse partition located below said radial ports and means for retaining said packing sleeves in place between said cylindrical valves and the inclosing walls of said valve chamber, all substantially 80 as and for the purpose specified.

In testimony whereof I affix my signature in the presence of two witnesses.

MATHIAS WEISSER.
